TOY TELEVISION TELEPHONE

Raymond Lohr, Erie, Pa., assignor to Louis Marx
& Company, Inc., New York, N. Y., a corpora-
tion of New York

Application February 3, 1936, Serial No. 62,146

46 Claims. (Cl. 46—33)

This invention relates to toys, and more particularly to a toy simulating a television telephone.

The primary object of my invention is to generally improve toy telephones by combining therewith simulated television apparatus. More particular objects deal with improvements in the telephone simulation itself as well as improvements in the television simulation.

One such object is to provide a picture reproduction which is luminous as though produced by television or like artificial means. To this end, the pictures are disposed on a suitable movable picture carrier, thus making the individual pictures selectively available, and the selected picture is directly illuminated by a lamp preferably disposed therebeneath.

The picture is observed through a suitable sight window. The television illusion is spoiled if the movement of the successive pictures is observed through the sight window. In accordance with a further feature and object of my invention, this outcome is prevented by the provision of a closure for the sight window, said closure being so related to the picture holder or the control means therefor, preferably a simulated calling dial, as to lock the same in position when the closure is open. The parts are unlocked when the closure is closed, but any movement of the picture holder at this time cannot be observed by the child using the device.

In accordance with further features and objects of my invention, the picture holder is moved or controlled by a simulated calling dial; the calling dial is restored to initial position by suitable resilient means, but the picture holder is held in dialed position by appropriate detent mechanism; the connection between the dial and the picture holder is uni-directional in order to permit free return of the dial; and the picture holder is restored to initial position when the telephone is hung up.

In order to position the sight window in most advantageous location, the dial and picture holder may be mounted on displaced centers and geared together for operative connection. Specifically, I prefer to locate the sight window at the center of the calling dial, and this arrangement results in an exceptionally neat and compact structure which does not substantially differ in over-all appearance from an ordinary telephone.

Another object of my invention resides in the provision of a leaf spring such as is used in snap-pers or the like, in order to produce a click when

the telephone is hung up by placing the hand-set on its supporting yoke. Still another object is to improve the realism of the toy by providing a suitable bell to simulate an incoming call, and this bell is preferably energized from the same battery cell that is used for the picture lamp. In accordance with a further object of the invention, the gong of the bell may be damped in order to change from a clear bell sound to a dull buzzer sound. This modified signal may be used as a calling signal preparatory to television operation. The battery circuit is preferably controlled by a multiple-position switch arranged to ring the bell in one position, to light the lamp in another position, and to ring but at the same time dampen the bell in a third position.

The picture holder carries a series of pictures at its periphery. In many cases the pictures may be of a character suitable for use by nearly all children, such as popular figures from newspaper comic strips and the like, and such pictures may, of course, be provided by the manufacturer of the toy. However, it is also desirable to make possible the addition of personal pictures, such as those of the immediate members of the child's family; and it is accordingly a desideratum of my invention to mount the pictures in a temporary or detachable manner on the picture holder. The toy is so constructed as to provide access to the picture holder, and the pictures may be changed at will, thus widening the range and play value of the toy.

To the accomplishment of the foregoing and other objects which will hereinafter appear, my invention consists in the toy telephone and toy television elements, and their relation one to the other, as hereinafter are more particularly described in the specification and sought to be defined in the claims. The specification is accompanied by drawings in which:

Fig. 1 is a front elevation of a toy television telephone embodying features of my invention;

Fig. 2 is an elevation taken in section, in the plane of the line 2—2 of Fig. 1;

Fig. 3 is a section taken in plan in the plane of the line 3—3 of Fig. 1;

Fig. 4 is a section taken in the plane of the line 4—4 of Fig. 1, and shows the manner in which the closure locks the dial;

Fig. 5 is a plan view of the picture holder mechanism, and is taken in the plane of the line 5—5 of Fig. 2;

Fig. 6 is a plan view of the switch and bell dampening mechanism;

Fig. 7 is an inverted plan view of the picture

holder, looking in the plane of the line 7—7 of Fig. 2;

Fig. 8 is a section through the periphery of the picture holder, and illustrates the manner in 5 which the pictures are detachably applied; and

Fig. 9 is a schematic wiring diagram showing the electrical circuit employed in the toy.

Referring to the drawings, particularly Fig. 1, the toy comprises a simulated telephone structure including a base B, a supporting yoke Y mounted thereon, and a removable hand-set H resting on said yoke and connected to the base through a flexible cord F. The hand-set comprises a simulated ear phone P and mouth piece or microphone M. It will be understood, however, that while the toy in the present example simulates a telephone of the French type, it is also possible to make the telephone of the desk or upright type, the mouth piece then being mounted at the 20 top of a pedestal projecting from the base, and the removable part including only an ear phone, rather than a complete hand-set, the ear phone being connected to the base by the flexible cord F. A simulated calling dial D is rotatably 25 mounted on the sloping top surface of the base B.

As thus far described, the toy simulates an ordinary telephone. However, the center portion of dial D is cut away to form a sight window at W normally closed by a suitable closure disc C. A 30 manually operable multiple-position switch control lever S projects from base B and may be used for a number of purposes subsequently described.

Considering the arrangement in greater detail and referring more particularly to Figs. 2 and 4, the dial D comprises a sheet metal disc 12 having a flanged outer edge 14. A plurality of guide and connecting fingers 16 are struck inwardly from the center of the disc and pass 40 through a mating opening formed on the top wall 18 of the telephone base B. This opening is defined by an outwardly bent flange 20. The inner ends of fingers 16 are received by and secured to a gear 22 the teeth 24 of which are preferably 45 bent downwardly, as shown in Figs. 2 and 4. Gear 22 meshes with a gear 26 rotatable on an upright spindle 28 displaced rearwardly a substantial distance from the center of the dial. The angularity between the axes of the dial and spindle 28 is taken care of by the bending of teeth 24 previously referred to. Constant meshing of gears 22 and 26 is preferably made certain by the provision of flange plates 30 on opposite sides of gear 26, the resulting laminated parts being held together by suitable eyelets 32 (Figs. 2 and 5).

Spindle 28 also carries a picture holder or disc 34. The peripheral or picture-holding portion of disc 34 is bent downwardly to a position substantially parallel to dial D and directly underlying the sight window W at the center of the dial, as will be evident from examination of Fig. 2. Picture holder 34 is moved or controlled by dial D through a uni-directional connection comprising simply a driving lug 36 (Fig. 2) depending 60 from gear 26, and a driven lug or stop 38 projecting upwardly from disc 34. Gear 26 is normally urged to initial position by a spring 40 coiled about spindle 28 and having one end secured to the base at 42, while the other end is secured to the gear at 44. Because gear 26 is in mesh with gear 22, the calling dial is likewise restored to initial position. This position is determined by means of a suitable stop 46 (Fig. 1) 70 projecting downwardly inside dial D and abutting

a stationary stop 48 projecting upwardly from the base.

Reverting to Fig. 2, the picture disc 34 is itself normally urged to initial position by a separate restoring spring 50 coiled about spindle 28 and having one end connected to a channel-shaped bar 52 extending transversely of the base, said bar being best shown in Figs. 3 and 6. The other end of spring 50 is connected to the hub of the picture holder, as is indicated at 54. The picture holder 34, unlike the dial, is locked against restoring movement by appropriate pawl and detent mechanism. Referring to Figs. 2 and 5, it will be seen that a series of detent teeth 56 are struck upwardly at the periphery of picture holder 34. A holding pawl 58 is pivotally mounted on the base by means of bearings 60. The pawl 58 is normally moved downwardly to locking position by means of a light leaf spring 62 bearing upwardly on the opposite end or extension 64 from pawl 58. The extension 64 underlies a vertically movable trip rod 66 which extends upwardly through a hollow pedestal or support 68 of yoke Y. The upper end of trip rod 66 rises to a position somewhat higher than that shown in Figs. 25 1 and 2 when the hand-set is removed from the yoke, and at the same time the pawl 58 moves downwardly to locking position. It will be seen that by removing the hand-set and dialing the dial D to any one of the appropriately numbered 30 finger holes therein, the picture disc 34 is turned to bring a corresponding picture beneath the sight window W. The dial is thereupon released and is immediately restored to initial position under the influence of spring 40. The picture disc 35 is held in the dialed position. When the telephone is hung up by replacing the hand-set on the supporting yoke, the trip rod 66 is depressed, thereupon elevating pawl 58 and permitting the picture disc to move back to initial position under 40 the influence of spring 50.

The sight window W is provided with a closure C, best shown in Figs. 1, 2, and 4. This closure is pivotally mounted at 70 on the inner end of a support arm 72 the outer end of which is secured to 45 the base at 74. It will be understood that the arm 72 overlies the dial and does not interfere with rotation thereof, although it also conveniently acts as a finger stop in order to limit the forward or clockwise rotation of the dial. The 50 closure is provided with a locking lug 76 (Fig. 4) dimensioned to fit into a mating slot 78 on the upper surface of the dial. Slot 78 comes into registry with locking lug 76 when the dial is in its position of rest, that is, when stops 46 and 48 55 (Fig. 1) are in abutment. At this time the closure is readily moved to open position, that is, from the solid line to the broken line position shown in Fig. 4. The closure when in open position locks the dial against movement, and it is 60 therefore impossible to advance the picture holder to another picture while looking through the sight window. This is of advantage in order not to expose too readily the mode of operation of the toy. On the other hand, when the closure 65 is moved to closed position, the dial is freely movable. The moment the dial is displaced from initial position, however, it becomes impossible to open the closure because the lug 76 bears against the upper surface of the dial instead of passing 70 through a slot such as slot 78. Slot 78 is nearer the inner edge of the dial than are the finger holes of the dial.

The picture holder is preferably arranged to facilitate replacement of the pictures carried 75

thereby. Referring to Figs. 5, 7, and 8, it will be seen that the picture disc 34 is reversely bent at its edge 80 to form a peripheral channel. A flat piece of spring metal 82 is secured to picture disc 34, the parts being mounted on a common collar or hub 84. Plate 82 is shaped to provide a series of outwardly projecting or radial lobes or fingers 86, there being one finger for each of the picture windows 88. The picture windows preferably exceed by one the number of dial or finger openings, thus providing a window corresponding to the rest or zero position of the dial. This window is, of course, not provided with a picture but may instead carry a suitable legend, or be left blank. The pictures are indicated at 90 and are held in place by inserting one end between the bottom side of disc 34 and the spring finger 86, while inserting the opposite end of the picture in the peripheral channel 80. The picture may be flexed downwardly, as is indicated in broken lines in Fig. 8 in order to facilitate its insertion on the picture holder. The picture is, of course, so cut out as to place the head or useful part of the picture directly over the picture opening 88. The tips of fingers 86 are bent downwardly, as shown in Fig. 8, to facilitate insertion of the pictures. In Fig. 2 the pictures have been omitted, except in section.

Access to the picture holder may be obtained in any desired manner. In the specific case here shown, the entire bottom 92 of the base (Figs. 1 and 2) is removable, the base being held in place by nuts 94, (Figs. 2 and 3), said nuts being threaded on studs depending from the transverse channel member 52 previously referred to. The channel member is secured to the side or peripheral wall of the base, as by the use of tongue and slot connections 96. When the base is removed, the battery cell, bell, lamp, and switch mechanism are removed therewith, and the picture holder is thus fully exposed and readily accessible for making any desired changes in the pictures carried thereby.

The picture is preferably disposed a substantial distance below the top or outer edge of the sight window W. This tends to darken the picture, which I consider desirable in order that the picture may not be seen except when intentionally illuminated. To illuminate the picture, I provide a lamp 100 of flashlight battery type, said lamp being screwed into a socket 102 mounted on the bottom 92. As will be seen in Fig. 2, the lamp is so positioned as to throw its illumination directly through the picture toward the sight window. The lamp is energized from a battery cell 104 of flashlight type (Fig. 3), this battery cell being held in place by spring fingers 106 riveted at 108 to the bottom 92. The holder 106 includes an end contact 110 which bears against one pole or terminal 112 of the cell 104, thus grounding the same. A support 114 is secured at the opposite end of the cell to bottom 92 by appropriate tongue and slot connections 116, said support 114 insulatedly carrying the end 118 of a wire 120 and holding the same in contact with the opposite end or pole of the cell.

Referring now to Fig. 9, it will be seen that the conductor 120 leads to a multiple-tongued switch plate 122 the tongues 124, 126, and 128 of which, respectively, overlie fixed contacts 130, 132, and 134. Contact 134 is connected by means of a conductor 136 to one terminal of the socket of lamp 100, the other terminal being grounded. It will be evident that by depressing switch tongue 126, a circuit is closed from cell 104 through lamp 100.

Reverting now to Figs. 1, 2, 3, and 6, it will be seen that I provide a switch control lever S which is movable both sidewardly and downwardly. The inner end of lever S is freely movable in a support plate 138, while the outer end cooperates with a forward notched plate 140, plates 138 and 140 preferably being formed from a single piece of sheet metal bent to U shape and secured to bottom 92, as is indicated at 142 in Fig. 2. The shape of forward plate 140 is indicated in Fig. 1, and it will be noted that this plate is provided with a horizontal slot 144 communicating with three depending slots 146, 148, and 150, so that the switch lever S may be moved to a position overlying any one of the depending slots and then depressed. It will be appreciated that the slots 146, 148, and 150 directly overlie the contact fingers 124, 126, and 128, thus making it possible to selectively close any of the three switches.

The switch plate 122 and the contacts 130, 132 and 134, are insulated from the metallic structure of the toy. Referring to Figs. 2 and 3, it will be seen that the plate 122 is secured to an insulation slab 152 by means of a rivet 154 and downwardly and reversely bent ears 156. The contacts 130, 132, and 134 are also mounted on insulation slab 152 which is itself supported between walls 138 and 140 at a point elevated above the bottom 92. The switch arm carries an insulation washer 158 which comes into contact with and depresses any one of the switch fingers when the switch arm is depressed. This insulation, of course, prevents undesired grounding of the circuit.

In order to enhance the realism of the toy, I provide an electric bell in the base. This bell may be of conventional type and is clearly shown in Figs. 2 and 3. The bell comprises a gong 160 and a clapper 162 mounted on the outer end of an armature 164 adapted to be vibrated by intermittent energization of a suitable magnet 166 the circuit to which is repeatedly broken by a conventional spring switch blade 168. Referring now to Fig. 9, it will be seen that contacts 130 and 134 are both connected to the bell magnet 166. The wiring diagram has been simplified by showing only the magnet of the bell, but it will be understood that the circuit really is complicated by the use of switch blade 168 mounted on the bell armature in order to make and break the magnet circuit as the armature vibrates. In the present toy the contact 130 is used for true bell ringing purposes, and when the switch lever is moved to the right (as shown in Fig. 3) and depressed, a true ringing bell sound is obtained simulating the signal for an incoming call.

When the switch lever is moved to the left (as shown in Fig. 6) and depressed, a muffled or deadened sound is produced, much like a buzzer sound. To obtain this result, I provide a damper 170 which may be moved against the gong 160, thus muting its sound. This result is preferably obtained automatically when using the switch lever, and for simplicity the rear end of the switch lever is reversely bent, as is clearly shown in Figs. 3 and 6, and provided with a knob 170 of relatively soft material, for example, rubber. The parts of the switch and bell are so dimensioned and relatively positioned that when the switch lever is moved to the left, the damper 170 is pressed against gong 160. This special signal adds variety and may be used to particularly indicate the incoming of a television call, in contradistinction to a mere telephone call.

The telephone mechanism may be further pro-

vided with means to simulate the click obtained when removing or replacing the receiver or hand-set of a real telephone. In the present case, I provide a reversely bent or shallow U-shaped leaf spring 172, best shown in Figs. 1 and 2. The bottom portion of spring 172 is secured to the middle portion of the yoke Y at 170. The outer ends of spring 172 normally rise to a position somewhat higher than that shown in Figs. 1 and 2. The spring is so shaped that a clicking sound is produced when the hand-set is removed and permits the ends of the spring to move upwardly. Conversely, when the hand-set is replaced, its weight depresses the ends of spring 172, thus again producing the desired click. It will be understood that the resistance of spring 172 must be made appreciably less than the weight of the hand-set in order not to interfere with the desired depression of the trip rod 66 by the hand-set. It will also be understood that the click spring need not be mounted in exposed position, as here shown, but may, if desired, be mounted in the base of the toy and operated by a suitable rod such as the trip rod 66.

23 The details of the telephone structure are relatively unimportant, but considered briefly, the base B is made of an upwardly dished or convexed piece of sheet metal closed at the bottom by the aforesaid removable bottom plate 92. The 30 post or support 68 is a tubular piece of sheet metal the lower end of which is secured to the top of the base by suitable tongue and slot connections, best shown in Fig. 2. The yoke Y is made of a piece of sheet metal 180 having guide 35 fingers 182 bent upwardly therefrom, and a front wall or apron 184 bent downwardly in front of the post 68. Apron 184 may, if desired, have secured thereto a piece of cardboard or other suitable surface 186 on which the names of the 40 various characters which may be called and seen through the sight window are listed. These characters are, of course, appropriately numbered in accordance with the numbering of the calling dial.

45 The hand-set is, in the present instance, made of sheet metal bent to suitable configuration, but it will be understood that other materials, particularly molded materials, may be employed, if desired.

50 It is believed that the mode of constructing and using, as well as the many advantages of my improved toy television telephone, will be apparent from the foregoing detailed description thereof. The structure resembles an ordinary telephone. The picture is preferably illuminated for distinctness and in order to give it a reddish glow better simulating television. The picture holder is entirely concealed within the telephone structure, and only one picture at a time may be 55 viewed through a suitable sight window. This window is provided with a closure so interlocked with the dial that when the closure is open, the dial cannot be moved, and, on the contrary, when the dial is moved the closure cannot be opened. This helps minimize the opportunity for watching the movement of the pictures while turning the dial, which would, of course, rob the toy of much of its mystery or illusion. The picture wheel is turned and controlled by a calling dial simulation. The latter has its own restoring means and is so 60 connected to the picture holder that the dial may immediately move back to initial position while the picture holder is locked in the position last dialed. On hanging up the telephone, however, 65 the picture holder is automatically restored to

70

75

initial position, thus bringing the dial and picture holder again into registry. This mode of control is obtained even though the dial and picture wheel are on greatly displaced centers, the displacement being selected for most advantageous 5 location of the pictures and sight window. In the present preferred construction, the sight window is located at the center of the calling dial,—a location which is convenient; results in a neat structural arrangement; and heightens the illumination as to the operation of the toy.

The pictures are detachably related to the picture holder, and pictures of personal interest may therefore be used. Means are provided producing an audible click when the hand-set is replaced 15 on its support, thus simulating the click of a real telephone when hanging up. An electric calling bell is included with the telephone, and additional means are provided whereby a subdued or buzzer-like tone may be produced instead of the true 20 bell ring, thus making available two separate audible signals in addition to the lamp control for picture illumination. These various matters are preferably all controlled by a single switch lever.

25 Although the telephone simulation here illustrated is of the hand-set type, it will be understood that it may also be made of the desk or upright type, in which case various functions, such as the restoration of the picture wheel to initial position, and the production of a click when hanging up, will be obtained by placing a receiver or ear phone on a suitable support, instead of placing a complete hand-set. The similarity is manifest because half of the hand-set is an ear phone. 30 It will therefore be apparent that while I have shown and described my invention in a preferred form, many changes and modifications may be made in the structure disclosed, without departing from the spirit of the invention, defined in 35 the following claims.

I claim:

1. A toy television telephone comprising a simulated telephone structure having an enlarged base, a picture holder movably mounted within 45 said base and carrying a plurality of pictures, a sight window, a simulated calling dial on top of said base, means whereby operation of the dial acts to move the picture holder to select one of the pictures thereon, a lamp, a battery cell concealed 50 in said telephone structure, and a switch for controlling the energization of said lamp, said lamp being so disposed as to illuminate the selected picture on the picture holder and to thereby make the same clearly visible in the aforesaid sight 55 window.

2. A toy television telephone comprising a simulated telephone structure, a movable picture holder associated therewith and concealed thereby, a sight window for exposing a picture, a closure for said sight window, means for moving the picture holder, and means whereby the picture holder is locked against movement while the closure is open, but is free for movement when the closure is closed.

3. A toy television telephone comprising a simulated telephone structure, a rotatable picture disc associated therewith and concealed thereby, a sight window for exposing one of said pictures at a time, a closure for said sight window, control 70 means for moving the picture disc in order to change the picture disposed in front of the sight window, and means whereby the control means is locked against movement while the closure is open, but is free for movement when the closure 75

- is closed, thereby concealing the picture disc when the latter is being moved by the control means.
4. A toy television telephone comprising a simulated telephone structure, a movable picture holder associated therewith and concealed thereby, a sight window for exposing a picture, a closure for said sight window, a dial for moving the picture disc, means to restore the dial to initial position, 10 and a lock associated with said closure whereby the closure is locked against opening while the dial is away from initial position, but is free for opening when the dial is in initial position.
5. A toy television telephone comprising a simulated telephone structure, a movable picture holder associated therewith and concealed thereby, a sight window for exposing a picture, a closure for said sight window, a dial for moving the picture holder, and means whereby the closure is 15 locked against movement while the dial is being moved.
6. A toy telephone structure comprising a base with a support thereon, a receiver connected to said base by a flexible cord and adapted to rest 20 on said support, a clicker spring arranged to be moved by the receiver when the telephone is hung up, said spring being so shaped that it audibly clicks when bent by the receiver.
7. A toy telephone structure comprising a base 25 with a support yoke projecting upwardly therefrom, a hand-set connected to said base by a flexible cord and adapted to be supported on said yoke, and a light clicker spring arranged to be moved when the hand-set is removed from or 30 placed on the yoke, said spring being so shaped that it audibly clicks when bent by movement of the hand-set.
8. A toy telephone structure comprising a base 35 with a support yoke projecting upwardly therefrom, a hand-set connected to said base by a flexible cord and adapted to be supported on said yoke, a resilient leaf clicker spring secured to said yoke and adapted to be bent by the weight of 40 the hand-set when the hand-set is placed on the yoke, said spring being so arranged that it audibly clicks when bent by the weight of the hand-set, thereby simulating the click attendant upon hanging up the telephone.
9. A toy television telephone comprising a telephone structure having an enlarged base, a picture wheel rotatably mounted in and concealed by the said base, a simulated calling dial on said base for moving said picture wheel, a sight window, a lamp for illuminating a picture and there- 45 by exposing the same in the sight window, a bell, a battery cell, and a multiple-position switch for energizing either the lamp or the bell at will.
10. In a toy telephone, a bell including a gong and a clapper, a battery cell, a multiple-position switch for connecting the bell and cell, and means for dampening the gong of the bell in order to produce a subdued buzzer sound, said means being automatically operative in one of the positions of the switch and inoperative in another, 50 whereby the bell may be rung as a bell or as a buzzer.
11. A toy television telephone comprising a telephone structure, a picture holder movably mounted on said telephone structure, a lamp for illuminating a picture, a bell including a gong and clapper, a battery cell, a multiple-position switch, and means to dampen the gong, said switch being adapted to energize the lamp in one 55 switch position, to energize the bell in another, 60 and to dampen the gong and energize the bell in a third switch position.
12. A toy television telephone comprising a telephone structure having an enlarged base, a picture wheel rotatably mounted and housed within said base, a simulated calling dial on said base for moving said picture wheel, a sight window, a lamp for illuminating one of said pictures and revealing the same in said sight window, a bell including a gong and clapper, a battery cell, 5 a multiple-position switch, and means to dampen the gong, said switch being arranged to energize the lamp in one switch position, to energize the bell in another switch position, and to dampen the gong and energize the bell in the third switch 10 position.
13. A toy television telephone comprising a telephone structure, a simulated calling dial rotatably mounted thereon, a sight window, a picture holder movably mounted in and concealed by the telephone structure, said holder being movable about an axis so displaced from the axis of the dial that the pictures thereon are movably disposed in desired relation to the sight window, and means so connecting the dial and 15 picture holder that movement of the dial moves the picture holder.
14. A toy television telephone comprising a telephone structure, a simulated calling dial rotatably mounted thereon, the center of said dial 20 being cut away to form a sight window, a picture holder movably mounted in and concealed by the telephone structure, said holder being movable about an axis so displaced from the axis of the dial that the pictures thereon are movably disposed beneath the sight window.
15. A toy television telephone comprising a telephone structure, a simulated calling dial rotatably mounted thereon, the center of said dial 25 being cut away to form a sight window, a picture holder movably mounted in and concealed by the telephone structure, said holder being movable about an axis so displaced from the axis of the dial that the pictures thereon are movably disposed beneath the sight window, and means so connecting the dial and picture holder that movement of the dial moves the holder.
16. A toy television telephone comprising a telephone structure, a simulated calling dial movably mounted thereon, resilient means normally tending to restore the same to initial position, 30 the center of said dial being cut away to form a sight window, a picture wheel rotatably mounted in and concealed by the telephone structure, said wheel being movable about an axis so displaced from the axis of the dial that the pictures thereon are movably disposed beneath the sight window, and means so connecting the dial and picture wheel that movement of the dial moves the picture wheel, said connecting means 35 between said dial and picture wheel being operable in only one direction, whereby the dial may be immediately restored to initial position by the aforesaid restoring means.
17. A toy television telephone comprising a telephone structure, a simulated calling dial movably mounted thereon, resilient means normally tending to restore the same to initial position, the center of said dial being cut away to form a sight window, a closure for said sight window, a picture wheel rotatably mounted in and concealed by the telephone structure, said wheel being movable about an axis so displaced from the axis of the dial that the pictures thereon are movably disposed beneath the sight window, means so 40

- connecting the dial and picture wheel together that movement of the dial may be used to move the picture wheel, said connecting means between said dial and picture wheel being operable in only 5 one direction, whereby the dial may be immediately restored to initial position by the aforesaid resilient restoring means, and means whereby said closure can be opened only when the dial is in initial position.
- 10 18. A toy television telephone comprising a telephone structure including a base with a sloping top surface, a simulated calling dial mounted on said sloping surface and movable about an inclined axis, a sight window, a picture disc mov- 15 ably mounted on and concealed within the base of said telephone structure, said picture wheel being movable about a vertical axis, means gearing said dial and picture wheel together whereby the dial may be used to move the picture wheel, the 20 peripheral portion of said picture wheel being disposed at an angle suitable for directing the pictures in desired direction with respect to the sight window, and pictures mounted on the peripheral portion of said picture wheel.
- 25 19. A toy television telephone comprising a telephone structure including a base with a sloping top surface, a simulated calling dial mounted on said sloping surface and movable about an inclined axis, a sight window, a picture wheel mov- 30 ably mounted on and concealed within the base of said telephone structure, said picture wheel being movable about a vertical axis, means gearing said dial and picture wheel together whereby the dial may be used to move the picture wheel, the 35 peripheral portion of said picture wheel being disposed at an angle suitable for directing the pictures in desired direction with respect to the sight window, pictures mounted on the peripheral portion of said picture wheel, and a lamp for illuminating said pictures in order to expose the same 40 in the sight window.
- 45 20. In a toy television telephone, a simulated telephone structure, a picture wheel rotatably mounted on and concealed in said structure, the peripheral portion of said wheel being disposed at an angle with respect to the center portion of the wheel, pictures mounted on the peripheral portion of said picture wheel, a simulated calling dial, means whereby operation of the dial acts to move 50 the picture wheel, and a sight window, the angularity of the peripheral portion of the picture wheel being such as to most advantageously dispose the pictures with respect to the sight window.
- 55 21. In a toy television telephone, a simulated telephone structure, a picture wheel rotatably mounted on and concealed in said structure, the peripheral portion of said wheel being disposed at an angle with respect to the center portion of 60 the wheel, pictures disposed on the peripheral portion of said picture wheel, means at the center portion of the wheel to detachably receive the inner ends of said pictures, a lamp for illuminating said pictures, and a sight window, the angularity 65 of the peripheral portion of the picture wheel being such as to most advantageously dispose the pictures with respect to the sight window.
- 70 22. A toy television telephone comprising a simulated telephone structure having an enlarged base, a picture holder movably mounted within and concealed by said base and carrying a plurality of pictures, a sight window in said base over the path of movement of said pictures, a simulated calling dial on top of said base, and means 75 whereby operation of the dial acts to move the picture holder to expose one of the pictures thereon directly in the sight window.
- 75 23. A toy television telephone comprising a telephone structure having an enlarged base with a removable bottom, a picture wheel rotatably mounted in and concealed by said base near the upper part thereof, a dial on top of said base for moving said picture wheel, a sight window, a lamp for illuminating a picture and thereby exposing the same in the sight window, a bell, a battery 10 cell, and a control switch therefor, said lamp, bell, cell and switch being mounted on and carried by the removable bottom of the base.
- 15 24. A toy television telephone comprising a telephone structure, a picture holder movably mounted in and concealed by said telephone structure, a sight window for exposing one of said pictures to view, a bell, means to dampen the sound of the bell, a battery cell, and a multiple-position switch mechanism arranged to operate 20 the bell in one position, and to energize the bell and at the same time to automatically dampen the bell when moved to another position.
- 25 25. A toy television telephone comprising a telephone structure, a picture wheel rotatably mounted in and concealed by said telephone structure, a sight window, a plurality of picture openings distributed about the periphery of the picture wheel, a disc made of resilient metal secured to the wheel at the center thereof, the periphery of said disc being shaped to form a plurality of independently movable spring fingers, and a plurality of separate independent pictures supported on said wheel at said picture openings with the inner ends of the pictures detachably 30 gripped by said spring fingers.
- 35 26. A toy television telephone comprising a simulated telephone structure having an enlarged base, a sight window, a picture holder movably mounted within said base and carrying a plurality of pictures, said pictures being printed on paper or other inexpensive material, and representing persons whom a child might wish to telephone, and a lamp, said lamp being so disposed as to illuminate one of the pictures on the 40 picture holder and to make the same clearly visible in the sight window.
- 45 27. A toy television telephone comprising a simulated telephone structure having an enlarged openable base, a picture holder rotatably mounted within said base and detachably carrying a plurality of separate independently removable pictures representing persons whom a child might wish to telephone, a sight window, and a lamp, said lamp being so disposed as to illuminate one of the pictures on the picture holder and to thereby make the same visible through the aforesaid sight window.
- 50 28. A toy television telephone comprising a simulated telephone structure, a picture holder movably mounted in and concealed by said telephone structure, a plurality of pictures, said pictures being printed on paper or other inexpensive material, and representing persons whom a child might wish to telephone, means on said picture holder for detachably receiving the individual pictures, whereby one or more of the pictures may be removed and replaced by others, and a sight window for exposing a picture on the picture holder, said telephone structure being 55 openable for access to the picture holder.
- 60 29. A toy television telephone comprising a simulated telephone structure, a picture wheel rotatably mounted in and concealed by said telephone structure, a plurality of pictures printed 65
- 70
- 75
- 80
- 85
- 90
- 95

on thin flexible translucent material and representing persons whom a child might wish to telephone, means on said picture wheel for detachably holding the pictures so that they may 5 be removed and replaced by others, and a sight window for exposing one of the pictures, the picture wheel serving to frame and support the flexible material on which the pictures are printed, but being cut away at each picture to expose 10 both sides thereof, and means for directing light against the back of the exposed picture.

30. A toy television telephone comprising a telephone structure, a plurality of pictures concealed within said structure, means to expose 15 one of the pictures to view, a lamp for illuminating the exposed picture, a bell, a battery cell, and switch means for selectively energizing either the lamp or the bell from the cell.

31. A toy television telephone comprising a 20 telephone structure, a picture holder movably mounted within and concealed by said telephone structure, means outside the structure to move the picture holder to expose a picture, a lamp for illuminating the exposed picture, a bell, a 25 battery cell, and a switch for selectively energizing either the lamp or the bell at will.

32. In a toy telephone, a bell including a gong, a clapper, and means to rapidly vibrate the clapper against the gong to produce a continuous 30 ringing sound like a telephone bell, and optionally usable means for dampening the gong of the bell during operation of the clapper in order to produce a continuous subdued buzzer sound.

33. In a toy telephone, an electrically operated 35 bell including a gong, a clapper, and electrical means to rapidly vibrate the clapper against the gong to produce a continuous ringing sound like a telephone bell, a battery cell for energizing said bell, and optionally usable means for dampening the gong of the bell during operation of the 40 clapper in order to produce a continuous subdued buzzer sound.

34. A toy television telephone comprising a 45 telephone structure, a picture holder movably mounted on said telephone structure and having a plurality of picture openings therein, means concealing said picture holder, a plurality of pictures of persons or things to whom a child 50 would wish to telephone, a sight window for viewing one of said pictures, and means on said picture holder for detachably receiving the pictures, whereby the pictures may be removed and replaced by others, said means being so arranged as to bend the pictures into close contact with 55 the back of the picture holder at the picture openings.

35. A toy television telephone comprising a simulated telephone structure, a simulated calling dial mounted thereon, a picture carrier movably mounted thereon and carrying a plurality 60 of independent pictures of different persons likely to be called by a child on the telephone, and means so connecting the dial and the picture carrier that movement of the dial may be used 65 to move the picture carrier and thereby select a desired picture.

36. A toy television telephone comprising a simulated telephone structure, a simulated calling dial mounted thereon, a picture wheel 70 mounted within and concealed by the telephone structure, said wheel carrying a plurality of independent pictures of different persons likely to be called by a child on the telephone, means connecting the dial and picture wheel whereby 75 movement of the dial moves the picture wheel to

select one of the pictures, and a sight window through which the selected picture may be seen.

37. A toy television telephone comprising a simulated telephone structure, a simulated calling dial mounted thereon, a picture wheel 5 mounted thereon, unidirectionally operative means connecting the dial and picture wheel whereby clockwise movement of the dial moves the picture wheel, resilient means to restore the dial to initial position, and means for holding the 10 picture wheel in dialed position.

38. A toy television telephone comprising a simulated telephone structure, a simulated calling dial mounted thereon, a picture wheel mounted on the telephone structure, unidirectionally operative means connecting the dial and picture wheel 15 whereby clockwise movement of the dial moves the picture wheel, resilient means to restore the dial to initial position, resilient means tending to restore the picture wheel to 20 initial position, and pawl and detent means for holding the picture wheel in position.

39. A toy television telephone comprising a simulated telephone structure, a simulated calling dial mounted thereon, a picture wheel mounted 25 in and concealed by the telephone structure, means connecting the dial and picture wheel whereby movement of the dial moves the picture wheel, a sight window through which the pictures may be seen, resilient means tending to restore 30 the dial to initial position, resilient means tending to restore the picture wheel to initial position, and pawl and detent means for holding the picture wheel in dialed position, said last mentioned means being inoperative to hold the dial whereby 35 the dial is immediately restored to initial position.

40. A toy television telephone comprising a telephone structure, a picture disc mounted on said telephone structure, means to move said picture disc to desired position, resilient means normally tending to restore the picture disc to initial 40 position, pawl and detent means for holding the picture disc in position, and means releasing the pawl and thereby restoring the picture wheel to initial position.

41. A toy television telephone comprising a stationary telephone structure, an ear phone movable with respect to said structure and connected thereto by a flexible cord, a picture disc mounted on said telephone structure, means to move said picture disc to desired position, resilient means normally tending to restore the picture disc to initial position, pawl and detent means for holding the picture disc in position, and means operative on "hanging up" the telephone for automatically releasing the pawl and thereby restoring the picture wheel to initial position.

42. A toy television telephone comprising a stationary telephone structure, a hand-set movable with respect to said structure and connected thereto by a flexible cord, a picture disc mounted within and concealed by said telephone structure, means to move said picture disc to desired position, resilient means normally tending to restore the picture disc to initial position, pawl and detent means for holding the picture wheel in position, and means operative on restoring the hand-set to the stationary structure for automatically releasing the pawl and thereby restoring the picture wheel to initial position.

43. A toy television telephone comprising a stationary telephone structure, a picture disc mounted within and concealed by said telephone structure, resilient means normally tending to restore the picture disc to initial position, pawl and 75

detent means for holding the picture disc in position, means for releasing the pawl and thereby restoring the picture disc to initial position, a simulated calling dial mounted on the telephone structure, and means connecting the dial and the picture disc.

44. A toy television telephone comprising a stationary telephone structure, an ear phone movable with respect to said structure and connected thereto by a flexible cord, a picture disc mounted on said telephone structure, resilient means normally tending to restore the picture disc to initial position, pawl and detent means for holding the picture disc in position, means operative on "hanging up" the telephone for automatically releasing the pawl and thereby restoring the picture disc to initial position when the telephone is hung up, a simulated calling dial mounted on the telephone structure, resilient means for returning the dial to initial position immediately after dialing a number, and unidirectionally operative means connecting the dial and the picture disc.

45. A toy television telephone comprising a stationary telephone structure, a hand-set movable with respect to said structure and connected thereto by a flexible cord, a picture disc mounted within and concealed by said telephone structure, resilient means normally tending to restore the picture disc to initial position, pawl and de-

tent means for holding the picture disc in position, means operative on restoring the hand-set to the stationary structure for automatically releasing the pawl and thereby restoring the picture disc to initial position, a simulated calling dial mounted on the telephone structure, resilient means for returning the dial to initial position immediately after dialing a number, and means so interconnecting the dial and the picture disc that the dial moves the picture disc to desired position but the dial is free to return to initial position.

46. A toy television telephone comprising a simulated telephone structure, a simulated calling dial mounted thereon, a picture wheel mounted within and concealed by the telephone structure, said wheel carrying a plurality of independent pictures of different persons likely to be called by a child on the telephone, means connecting the dial and picture wheel whereby movement of the dial moves the picture wheel to select one of the pictures, a sight window through which the selected picture may be seen, resilient means tending to restore the picture wheel to initial position, and manually releasable detent means for holding the picture wheel in selected position.

RAYMOND LOHR.
